United States Patent Office

Des. 191,152
Patented Aug. 15, 1961

191,152

BLENDER

Paul O. Rawson, Jr., Trumbull, Conn., and Frank M. Grunwald, Syracuse, and Robert I. Gresens, Rochester, N.Y., assignors to General Electric Company, a corporation of New York

Filed Mar. 27, 1951, Ser. No. 64,505

Term of patent 14 years

(Cl. D89—1)

Des. 191,152

PAGE 2

Fig. 2.

Des. 191,152

PAGE 3

Fig. 4.

Fig. 5.

FIG. 1 is a perspective view of a blender embodying our design;

FIG. 2 is a front elevation view of the blender;

FIG. 3 is a side elevation view of the blender;

FIG. 4 is a top plan view of the blender; and

FIG. 5 is a cross-sectional view taken along the line 5—5 in FIG. 2.

The dominant features of the design reside in the portions shown in full lines.

We claim:

The ornamental design for a blender, substantially as shown and described.
